ANTISPREADING DEVICE

Filed Jan. 28, 1929

Willard E. Everett

INVENTOR

BY Victor J. Evans

ATTORNEY

WITNESS: *G. L. Wright*

UNITED STATES PATENT OFFICE

WILLARD E. EVERETT, OF CUMBERLAND, MARYLAND

ANTISPREADING DEVICE

Application filed January 28, 1929. Serial No. 335,592.

This invention relates to an anti-spreading device for the rails of a track, the general object of the invention being to provide a simple form of tie means for connecting the two rails of a track together, so that the rails are prevented from spreading, with means for preventing the tie means from electrically connecting one rail with the other.

10 This invention also consists in certain other features of construction and in the combination and arrangement of the several parts, to be hereinafter fully described, illustrated in the accompanying drawing and 15 specifically pointed out in the appended claim.

In describing the invention in detail, reference will be had to the accompanying drawing wherein like characters denote like 20 or corresponding parts throughout the several views, and in which:—

Figure 1 is a plan view of a track, showing the invention in use.

Figure 2 is a section on line 2—2 of Figure 1.

Figure 3 is a perspective view of the tie member.

Figure 4 is a transverse sectional view showing the insulation on the tie member.

30 Figure 5 is a view showing a modification where the tie strip is formed with a straight end having a perforation therein.

Figure 6 is a sectional view showing this modification in use.

35 Figures 7 and 8 are views showing another modification.

Figures 9 and 10 are views showing a further modification.

In these views, the numeral 1 indicates a 40 strip which has one end of hook shape, as shown at 2, and its other end is bent upwardly at right angles, as shown at 3. The hooked end is passed under the rail A and the hook part placed in engagement with the outer part of the base of the rail. A 45 strip 4 of non-conducting material is placed between the rail and the strip, so as to insulate the strip from the rail. As shown in Figure 4, the material is of channel-shaped 50 form to overlap the edges of the strip 1.

The end 3 is passed through a hole formed in the splice bar C of the rail B and a cotter pin 5 is passed through a hole 6 formed in this part 3 of the strip. Thus the two rails are tied together by the strip so that 55 there is no danger of the rails spreading, and by insulating this strip 1 from the rail A, there is no danger of the strip electrically connecting the two rails together.

In the modification shown in Figures 5 60 and 6, the end of the strip 1' is not bent up, as in the first form, so that this straight end extends under the chair and is fastened to the inner side part of the chair by the bolt 7 which passes through the perforation 6' in the straight end of the strip.

In the modification shown in Figures 7 70 and 8, the strip 1'' is of such a length that it will extend entirely under the splice bar and has its end bent up, as at 3', to engage the outer side wall of the splice bar, and this strip is also provided with a perforation 6'' 75 to receive a bolt 7' which passes through the inner side part of the splice bar, as clearly shown in Figure 8.

In the modification shown in Figures 9 80 and 10, the end of the strip 1'' which engages the splice bar, is of substantially hook shape, as shown at 8, with the beak of the hook extending downwardly so that it can pass through a slot in the splice bar C', as shown in Figure 9, with a cotter pin 5' passing through a perforation 6'' in the beak.

Thus in all the modifications, I have provided simple means for connecting the two rails of a track, so that there is no danger of the rails spreading, the connecting means between the rails being such that such means can be easily and quickly put in place and removed, when necessary.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

In combination with the rails of a track and a splice bar for one rail, said bar having a hole in its base part, a strip having a hook-shaped part at one end thereof adapted to engage the base of one rail, a hook forming part at its other end for engaging the hole in the splice bar, the last mentioned hook shaped part being formed by bending the strip upwardly and then forwardly and then downwardly, with the downwardly extending part passing through the hole in the bar and a pin passing through the extremity of the downwardly extending part and engaging the under face of the bar.

15 In testimony whereof I affix my signature.

WILLARD E. EVERETT.
